[57] CLAIM

The ornamental design for a shelf, substantially as
shown and described.

DESCRIPTION

FIG. 1 is a front elevational view of a shelf showing my
new design;

FIG. 2 is a rear elevational thereof;

FIG. 3 is a right side elevational view thereof, the left
side elevational view thereof being a mirror image; and
FIG. 4 is a perspective view taken from the top at the
right side front corner of the shelf, the shelf having the
same appearance when viewed in perspective from the
bottom.

FIG. 1

FIG. 2

FIG. 4

FIG. 3
